CLAIM

The ornamental design for a golf ball, as shown and described.

DESCRIPTION

FIG. 1 is a front, top, left side perspective view of a golf ball, showing the new design;

FIG. 2 is a left side plan view of the golf ball;

FIG. 3 is a right side plan view of the golf ball;

FIG. 4 is a front plan view of the golf ball;

FIG. 5 is a rear plan view of the golf ball;

FIG. 6 is a top plan view of the golf ball; and,

FIG. 7 is a bottom plan view of the golf ball.

(Continued)

The broken lines shown in the drawings depict portions of the golf ball that form no part of the claimed design.
